DESIGN FOR A STREET AND HIGHWAY MARKER OR LIKE ARTICLE

John A. Harriss, New York, N. Y.

Application December 11, 1933, Serial No. 50,023

Term of patent 3½ years

To all whom it may concern:

Be it known that I, John A. Harriss, a citizen of the United States, residing at New York city, in the county of New York and State of New York, have invented a new, original, and ornamental Design for Street and Highway Markers or Like Articles, of which the following is a specification, reference being had to the accompanying drawing, forming part thereof.

Figure 1 is a perspective view of a street and highway marker, showing my new design.

Figure 2 is a transverse sectional view taken on the plane indicated by line 2—2 of Figure 1.

I claim:

The ornamental design for a street and highway marker or like article, as shown.

JOHN A. HARRISS.
